UNITED STATES PATENT OFFICE.

FRANK E. BECKMAN, OF HAVERHILL, MASSACHUSETTS, ASSIGNOR TO UNITED SHOE MACHINERY CORPORATION, OF PATERSON, NEW JERSEY, A CORPORATION OF NEW JERSEY.

SOLE-MOLDING PRESS.

Application filed March 16, 1920. Serial No. 366,265.

To all whom it may concern:

Be it known that I, FRANK E. BECKMAN, a citizen of the United States, residing at Haverhill, in the county of Essex and State 5 of Massachusetts, have invented certain new and useful Improvements in Sole-Molding Presses; and I do hereby declare the following to be a full, clear, and exact description of the invention, such as will enable others 10 skilled in the art to which it appertains to make and use the same.

This invention relates to presses for molding soles and is disclosed in connection with a machine for molding or breaking down 15 the margins of soles for turn shoes. The machine is designed for performing the specific operation of molding the margin about the toe end of a turn sole, to facilitate the first lasting and sewing operations the molding 20 of the adjacent portions of the margin being performed on another machine.

Heretofore it has been the practice to break down the margins of turn soles by feeding the margin of the sole progressively 25 past the molding tools of a machine such, for example, as the Goodyear power molding machine disclosed in Letters Patent of the United States to William C. Meyer No. 1,110,637, granted September 15, 1914. It 30 has been found to be difficult to feed, through a machine of this type, the extremely pointed toes on the soles now in vogue, commonly called "peaked toe" soles, without 35 distorting the toe and thus spoiling the lines of the shoe when finished.

The principal object of the present invention is to eliminate all danger of distorting the toe of a sole during the operation of breaking down the margin and an ancillary 40 object is to correct any distortion that may have occurred when the sole was rounded or fitted.

Accordingly an important characteristic 45 of the invention is found in the construction and arrangement of the devices for molding the toe end of the sole. In the preferred embodiment of the invention these devices comprise a mould couple comprising male and female moulds so shaped as to produce about the toe of a sole placed therebetween, an accurately moulded margin according with the size and style of the sole. Furthermore, because of the confinement of the sole between the moulds, a sole which may

be out of shape because of inaccurate rounding is reshaped to the exact outline required for perfect shoemaking. The moulds are of such proportions as to break down the margin of the sole for a distance of about one and one-half inches from the tip of the toe, 55 i. e., to about the tip line. The adjacent portions of the margin, preferably but not necessarily after this operation, are moulded by another machine which may be of the type disclosed in said patent of William C. Meyer 60 hereinbefore referred to. The soles are in temper when operated upon by the toe molding machine and are left under a brief sustained pressure to permit the moulded margin to set. Thus after removal from the 65 machine the moulded soles may be handled without harm to the toe end since the broken down margin is stiff and immovable. Preferably the machine is designed to support several mould couples each for receiving 70 a sole of different width and thus avoid too frequent adjustments.

To the accomplishment of this object and such others as may hereinafter appear, as will be readily understood by those skilled 75 in the art, the invention comprises the features and combination of parts hereinafter described and then particularly pointed out in the appended claims.

The features of the invention herein 80 claimed will be best understood from a description of the preferred embodiment thereof illustrated in the accompanying drawings, in which:

Figure 1 is a front elevation of the working parts of the machine; Fig. 2 is a side elevation of the mould supporting members of the machine; Fig. 3 is a plan of the upper or male mould supporting head, detached; Fig. 4 is a plan of the lower or female mould, detached; Fig. 5 is a perspective of the fore part of a turn sole after its toe has 90 been moulded; and Fig. 6 is a cross-section of the sole shown in Fig. 5 on the line 6—6 of said figure.

In the embodiment of the invention illustrated in the drawings the sole moulds have been applied to a press of the type disclosed in Letters Patent of the United States No. 514,364, granted Feb. 6, 1894, on the application 95 of Lorenzo P. Hawkins. As in the machine of said Hawkins patent a table 10, supported at a convenient height, is pro-

vided with a base block 12 having oppositely disposed ears 14. The lower or female mould block 16 is removably secured to the base block by screws 17 threaded into definitely located receiving bores in the ears 14.

Above the mould block 16 is a vertical bearing 18 carried at the forward end of the overhanging frame 20 which rises from the table at the rear end of the base block 12. A plunger 22 is fitted to slide in this bearing, to the upper end of which is suitably jointed the rod 24 of an eccentric strap 26 embracing an eccentric 28 on the forward end of a power shaft 30 driven by a pulley 32. Two journals for the shaft 30 rise from the frame 20 of which the forward one 34 only is shown. The revolution of the shaft 30 is controlled by a clutch (not shown), operated by a treadle attached to the treadle rod 36, designed to provide for a sustained pressure on the sole placed between the moulds as is common to presses of this general type.

The upper or male mould is secured to the lower face of a spilt block or head 38 having the construction shown in Figs. 1 and 3, a bolt 40 serving to clamp it on the lower end of the plunger 22. A centering pin 42 (dotted lines Fig. 1) serves to locate the head on the plunger and a pair of guide pins 44 engage bores 46 in the lower mould block 16. The male mould is thus exactly centered over the female mould.

In order to avoid frequent adjustment for size or style it is desirable to provide each mould block with a series of moulds, each couple differing from the others. In the illustrated embodiment of the invention each block is provided with three moulds representing three different sole widths. The lower block 16 is formed in one piece the female moulds being produced by recesses 48 of the required formation, i. e., generally triangular, in its upper face. The male moulds 50 are independent of each other, each mould being received and located on the lower face of the block 38 by a centering pin 52 (dotted lines Fig. 2) and removably held in position by a set screw 54 passing through an ear 56 which bears against the front face of the block 38. The machine will be equipped with such additional mould couples as may be required for all the styles and widths used in any particular factory and it will be observed that the mountings described provide for speedy interchangeability. This forms an important feature of the invention.

The molds are so designed as to break down the margin of the sole to the extent shown in Figs. 5 and 6. For good shoe-making the break on the grain side of a turn sole should be directly opposite the shoulder on the flesh side. Accordingly the inner wall 58 (Fig. 4) of the female mould

corresponds in shape to the shoulder on the sole and its height is equal to the depth of the shoulder. The outer wall 60 corresponds in shape to the edge of the sole. This feature is not essential but it is desirable since this wall serves as a gage to correctly locate the toe of the sole above the cavity formed by the inner wall 58. The lower surface 62 (Fig. 1) of the male mould is so proportioned as to form the break on the grain side opposite the shoulder on the flesh side when the descent of the plunger 22 forces the two moulds together. The oblique walls 59 and 61 of the two moulds are of such angularity to the horizontal surfaces as may be required to give the desired offset to the margin of the sole which may have been shouldered for incorporation in either a mock welt or a feather edged turn shoe.

In using the press a turn sole, which has first been fitted with a marginal shoulder by a suitable stock fitting machine such, for example, as disclosed in Letters Patent of the United States No. 1,030,704 granted June 25, 1912, on the application of Frederic E. Bertrand is placed with its toe end within and in contact with the wall 60 of the proper sized lower mould. The body portion of the sole extends outwardly through the open end of the mould recess and may be held by the operator without danger of injury to him. The clutch is then thrown in and the upper mould 50 descends forcing the shoulder down within the lower wall 58 thus reshaping the toe should this be necessary. The oblique walls 59 and 61 of the lower and upper moulds grip the margin outside the shoulder and cooperate to break it down to the extent permitted by their obliquity to the horizontal surfaces of the mould couple. It will be observed, as shown more particularly by Fig. 4, that the ends of the female mould walls are flared at the open end of the mould so as to avoid an injurious break at the tip line and provide for a merging of the moulded margin into the unmoulded margin to the rear thereof. As hereinbefore explained the portions of the margin opposite the shoulder at the opposite sides of the sole may be broken down in any convenient manner, preferably by the progressive pressure type of machine heretofore in use.

The present inventor believes himself to be the first to produce a sole having the margin at its toe end only moulded to the exact form required, and a machine for making it. Those skilled in the art will recognize the advantage of performing this operation with closed moulds of the exact shape of the toe which effectually prevent distortion and act to reshape the toe if this is required. Neither has the within described process of completely molding the

5 margins of peaked toe soles, partly by a molding pressure and partly by a progressive pressure, been practiced prior to the production of the novel turn sole illustrated

5 by Fig. 5.

10 The novel method of making soles above discussed is not claimed herein, but is fully set forth and claimed in United States Letters Patent No. 1,434,521, granted Nov. 7, 1922, on my application.

15 The nature and scope of the present invention having been indicated and the preferred embodiment of the invention having been specifically described, what is claimed as new, is:—

20 1. A molding machine for breaking down the margin at the toe end only of soles having, in combination, a female mould having a wall shaped to receive the toe end 25 of the sole and accurately fit it, a male mould opposite the female mould at the grain side of the sole, said moulds having co-operating oblique margin molding walls, and means for causing relative approach of said moulds to shape said margin of the sole by pressure between said oblique walls to facilitate the entrance of the needle in the sewing operation.

25 2. A molding machine for breaking down the margin at the toe end only of previously shouldered turn soles having, in combination, a female mould having a wall shaped to receive the toe end of the sole and accurately fit about the shoulder thereof, and 30 a gage for correctly locating said toe end relative to said wall, a male mould opposite the female mould at the grain side of the sole, said moulds having co-operating oblique margin moulding walls, and means for causing relative approach of said moulds to shape said margin of the sole by pressure between said oblique walls.

35 3. A molding machine for breaking down the margin at the toe end only of previously shouldered turn soles having, in combination, a female mould generally triangular in plan and open at its base the wall of which comprises a lower, vertical, shoulder engaging portion and an upper, oblique, 40 margin engaging portion, a solid male mould having an oblique margin engaging wall adapted to be seated within the oblique wall of the female mould, and means for causing relative approach of said moulds to shape said margin of a sole inserted therebetween by pressure between said oblique walls.

45 4. A press for molding the margin at the toe end only of soles having, in combination,

a bed supporting a female mould generally triangular in plan and open at its base the 50 wall of which comprises a lower, vertical portion and an upper, oblique, portion; a plunger supporting a solid male mould having an oblique margin engaging wall adapted to be seated within the oblique wall of the 55 female mould; and means to actuate said plunger to force a sole laid upon said female mould into said mould and shape said margin by pressure between said oblique walls.

60 5. A press for molding the margin at the toe end only of soles having, in combination, a bed supporting a female mould generally triangular in plan and open at its base the 65 wall of which comprises a lower, vertical portion, an upper, vertical, edge and a connecting oblique, portion; a plunger supporting a solid male mould having an oblique, margin engaging wall adapted to be seated within the oblique wall of the female mould, and means to actuate said 70 plunger to force a sole, located within the female mould by engagement of its toe end with the upper, vertical portion thereof, into said mould and shape said margin by pressure between said oblique walls.

75 6. A press for molding the margin at the toe end only of peaked toe soles having, in combination, a female mould generally triangular in plan and open at its base to permit the body of the sole to extend therethrough; a male mould of similar form; said moulds having oblique walls to engage the margin of the sole at each side and co-operate to break down said margin; and means for causing relative approach of said 80 moulds.

85 7. A press for molding the margin at the toe end only of turn soles having a female mould shaped to receive the end of a sole, a male mould of similar form, said moulds 90 having oblique walls to engage the margin of the sole at each side and co-operate to break down said margin, and guiding and operating means for causing relative approach and registration of said moulds.

95 8. A press for molding the margin at the toe end only of soles having a female mould member constructed and arranged to accommodate sole ends of a range of widths, a male mould member of similar characteristics, said mould members having oblique walls to engage the margin of the sole at each side and co-operate to break down said margin, and means for causing relative approach of said moulds.

100 FRANK E. BECKMAN.
